UNITED STATES PATENT OFFICE.

ROBERT M. DIXON, OF EAST ORANGE, NEW JERSEY, ASSIGNOR, BY MESNE ASSIGNMENTS, TO STANDARD HEAT AND VENTILATION COMPANY, INC., OF NEW YORK, N. Y., A CORPORATION OF NEW YORK.

HEATING SYSTEM.

1,062,639.

Specification of Letters Patent.

Patented May 27, 1913.

Application filed May 9, 1907. Serial No. 372,759

To all whom it may concern:

Be it known that I, ROBERT M. DIXON, residing at East Orange, in the county of Essex and State of New Jersey, have invented 5 certain new and useful Improvements in Heating Systems, of which the following is a full, clear, and exact description, such as will enable others skilled in the art to which it appertains to make and use the same.

10 My invention relates to heating apparatus and more particularly to systems adapted for heating railway cars or like structures.

One of the objects of my invention is to provide a heating system wherein the internal pressure may be maintained at substantially that of the atmosphere without regard to the normal pressure within the train 15 pipe.

Another object thereof is to provide a 20 heating system of the above type which may be installed and maintained at a minimum of cost, and such that the proper regulation of the radiating system with regard to the amount of heat units necessary to heat the 25 car properly under varying climatic conditions may be effected with greater facility and exactness.

A further object of my invention is to provide automatic regulating means for a 30 heating system of the above type which will operate in an accurate manner though constructed of comparatively few parts.

Other objects will be in part obvious and in part pointed out hereinafter.

35 The invention accordingly consists in the features of construction, combinations of elements and arrangement of parts which will be exemplified in the construction herein-after set forth, and the scope of the application of which will be indicated in the following claims.

In the accompanying drawings, wherein is illustrated one of the various possible embodiments of my invention, Figure 1 is a 45 view in perspective showing a floor plan of a railway car equipped with a heating system constructed in accordance therewith; Fig. 2 is a view in plan partly broken away and partly in section showing the means employed for regulating the system; Fig. 3 is a view partly in elevation and partly in section of that part of the mechanism illustrated in Fig. 2.

Similar reference characters refer to simi-

lar parts throughout the several views of the 55 drawings.

Referring now to the drawings, the train pipe 1, which is shown in dotted lines as extending longitudinally of the car beneath the floor, is supplied with steam under pressure from the locomotive. Branch pipes as at 2, and 3, extend laterally from the train pipe to supply steam for independent radiating systems which in the present instance are arranged at each side of the car. Inasmuch as the radiating systems located upon either side of the car are identical, but one of these need be described, in order to impart a clear understanding of my invention, and for convenience the one upon the right 60 hand side will be described herein.

Branch pipe 3, which extends laterally from the train pipe, is furnished with a manually operated valve as at 4, through the instrumentality of which the steam may 65 be entirely shut off from the radiating system which is supplied thereby. This branch pipe leads into a fitting 5 into which a feed conduit 6 is threaded, said feed conduit at its opposite end having a threaded connection with a casting 7. Casting 7 is provided with upwardly inclined passageway 8, and communicating with this passageway and extending from either end longitudinally of the car toward either end thereof are radiating pipes 9. Pipes 9 have, at their outer 70 ends, return elbows 10, from which extend return pipes 11, the latter being threaded into casting 7 and communicating with a passageway 12 into which is threaded discharge conduit 13, which extends inwardly in parallel relation to feed conduit 6. At this point, it may be noted that feed conduit 6 is formed of a metal of relatively low coefficient of expansion, in the present instance iron, and that discharge conduit 13 is 75 formed of a metal of relatively high coefficient of expansion, in the present instance brass.

Threaded upon the outer end of discharge 80 conduit 13 is a conduit 14 which in the present instance is of substantially the form of a return elbow, said conduit having a drainage aperture 15 in its lower portion which communicates with the atmosphere by means 85 of a downwardly extending pipe 16. Access to conduit 14 may be had by means of a plug 17 threaded therein.

Leading from conduit 14 and extending within fitting 5 of feed conduit 6 is a tubular injector member 18, the outer end of which extends externally of conduit 14 and is preferably squared or formed of polygonal shape to receive a wrench or any other turning instrument, by means of which said injector member may be adjusted for a purpose which will hereinafter be apparent. A lock nut 19 threaded exteriorly of injector member 18 takes against conduit 14 and holds said injector member in fixed position after adjustment. Injector member 18 is provided with a plurality of lateral apertures 20 which furnish a means of communication between the interior thereof and the conduit 14, and at its opposite end said member is flared as at 21, said flared portion constituting a valve which co-operates with a seat 22 formed upon the inner portion of fitting 5. Fitting 5 is provided with a chamber as at 23, into which leads branch pipe 3, valve 21 being interposed between the point of entrance of the branch pipe and feed conduit 6. The outwardly flared portion of injector member 18 and a seat 22 of fitting 5 form a narrow passageway 24, through which the steam under pressure from the steam pipe is injected into feed conduit 6, the injection of the steam operating to carry into the feed conduit a quantity of air which flows upward into the system through drainage opening 15, conduit 14, and thence through injector member 18. In order that injector member 18 may be moved relatively to fitting 5 as when valve portion 21 is moved relatively to its seat, within the outer end of said fitting is formed a gland 25, the members of which are held in position by a cap-piece 26 threaded exteriorly of the fitting. By means of this construction, injector member 18 may slide backward and forward within the fitting when the valve is opened or closed during the operation of the apparatus.

Having thus described the structural features which constitute this embodiment of my invention, the operation thereof may now be understood. Assuming the parts to be in the position shown in Fig. 2 of the drawings, steam under pressure from the train pipe will flow through branch pipe 3 into fitting 5 and be injected into feed conduit 6, which operation will, of course, cause a mixture of air and steam to flow through the feed conduit into the radiating system, said vaporous mixture leaving the radiating system through discharge conduit 13 and the water of condensation formed therein discharging through drainage aperture 15 to the atmosphere. Any uncondensed vapor in the discharge conduit will again be drawn into the feed conduit by the injector, and will again pass through the radiating system. The heated vapor passing first

through feed conduit 6 will cause the same to expand, which will tend to further enlarge the passageway between valve portion 21 and its seat, and this condition will continue to exist until the vapor passing through the radiating system and returning through discharge conduit 13 shall be of such temperature as will cause discharge conduit 13 to expand to a degree sufficient to cause valve 21 to be forced against its seat, thereby shutting off the supply of steam from the train pipe. When, however, due to radiation from the system of piping within the car, the temperature of the returning vapor is such as to cause a contraction of discharge conduit 13, valve 21 will be automatically forced from its seat again admitting steam to the feed conduit. Injector member 18 may be adjusted, as hereinbefore described, to regulate the dimensions of the injector passageway, whereby such different quantities of steam will be utilized as are required to keep the car at the desired temperature under varying climatic conditions.

It will accordingly be seen that I have provided a vapor heating system which is especially well adapted to attain the several ends and objects of my invention in an efficient manner, and while the same possesses all the advantages inherent in vapor heating systems as regards the reduced cost of installation and maintenance, less liability of breakage owing to the fact that only atmospheric pressure is required within the system and the fact that lighter and less expensive radiating pipes may be employed, it has the further advantage of being constituted by comparatively few parts coupled with a greater nicety of regulation.

It will be understood that under normal conditions the adjustment of the valve will be such as will permit a steady and uniform flow of steam to be injected into the feed conduit which, mixing with the injected air, will form a circulating vapor of substantially even temperature.

While I have shown my invention as applied to a railway car, it is of course obvious that the same may be employed with great facility in many other analogous relations, although the same is particularly adapted in the relation shown.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of

the invention which, as a matter of language, might be said to fall therebetween.

Having described my invention, what I claim as new and desire to secure by Letters

5 Patent is:

1. In a heating system, in combination, a radiating system, a feed conduit leading thereinto, a discharge conduit leading therefrom, and a valve for controlling the admission of steam into said radiating system the operation of which is determined by the differential expansion and contraction of said feed and discharge conduits.

2. In a heating system, in combination, 15 a radiating system, a feed conduit leading thereinto, a discharge conduit leading therefrom, and means controlled by the differential expansion and contraction of said feed and discharge conduits for regulating 20 the amount of steam admitted into said feed conduit.

3. In a heating system, the combination 25 with a radiating system, of a feed conduit leading thereinto, a source of air supply communicating with said feed conduit, means for injecting steam into said feed conduit, a discharge conduit for said radiating system, and a valve for controlling the 30 injection of steam into said feed conduit the operation of which is determined by differential expansion and contraction of said feed and discharge conduits.

4. In a heating system, the combination 35 with a radiating system, of a source of heat supply, a feed conduit connecting said source of supply with said radiating system, means for injecting steam into said feed conduit, a discharge conduit for said radiating system, and a valve for controlling the 40 amount of steam injected into said feed conduit the operation of which is determined by differential expansion and contraction of said feed and discharge conduits.

5. In a heating system, the combination 45 with a radiating system, of a source of steam supply, a feed conduit connecting said source of supply with said radiating system, means for injecting the steam into said feed conduit, a discharge conduit for said radiating system having a co-efficient of expansion different from that of said feed conduit, and a valve for controlling the injection of steam into said feed conduit the operation of 50 which is controlled by differential expansion and contraction of said feed and discharge conduits.

6. In a heating system, a radiating system, a feed conduit formed of a metal having a relatively low co-efficient of expansion 60 leading thereinto, a discharge conduit formed of a metal having a relatively high co-efficient of expansion, and a valve for controlling the admission of steam to said radiating system the operation of which is

determined by differential expansion and contraction of the feed and discharge conduits due to the internal heat conditions within the radiating system.

7. In a heating system, in combination, a radiating system, a feed conduit leading thereinto, a source of steam supply for said feed conduit, a discharge conduit leading from said radiating system, an injector carried by said discharge conduit and extended within said feed conduit, and a valve constituted by portions of said injector and said feed conduit, the differential expansion and contraction between said feed and discharge conduits operating to open and close 75 said valve.

8. In heating apparatus, in combination, a steam conduit forming a portion of a continuous regulating system, an inlet valve leading to said conduit and arranged to be controlled in accordance with the difference 85 in expansion and contraction of two portions of said conduit.

9. In a heating system, the combination 90 with a radiating system, a feed conduit open to the atmosphere leading thereinto, an injector extending within said feed conduit, a discharge conduit, and a valve constituted by said injector and said feed conduit adapted to be opened or closed by differential expansion and contraction of said feed and 95 discharge conduits due to differences in the temperature of the heating medium within the same.

10. In a heating system, the combination; 100 of a radiating system open to the atmosphere, a feed conduit leading into said radiating system, an injector extending into said feed conduit and having a sliding connection therewith, a discharge conduit with which said injector has fixed relation, and a valve between said injector and said feed conduit adapted to be opened or closed by the differential expansion and contraction of said feed and discharge conduits.

11. In a heating system, the combination 110 of a radiating system open to the atmosphere, a feed conduit leading into said radiating system, an injector extending into said feed conduit and having a sliding connection therewith, a discharge conduit with 115 which said injector has fixed relation, and a valve comprised by a seat within said feed conduit, and a portion of said injector adapted to contact therewith, the operation of said valve being determined by the differential expansion and contraction of said feed and discharge conduits.

12. In heating apparatus, in combination, a steam conduit forming a part of a continuous regulating system and comprising 125 different portions of material having different co-efficients of expansion, an inlet valve leading to said conduit and arranged

- to be controlled in accordance with the difference in expansion and contraction of said portions of said conduit.
13. In heating apparatus, in combination, a steam conduit forming a part of a continuous regulating system and comprising two connected and substantially parallel portions, an inlet valve leading to said conduit and arranged to be controlled in accordance with the difference in expansion and contraction of said portions of said conduit.
14. In heating apparatus, in combination, a steam conduit forming a part of a continuous regulating system and having two connected and substantially parallel portions, said portions being respectively of material having different co-efficients of expansion, an inlet valve leading to said conduit arranged to be controlled in accordance with the difference in expansion and contraction of said portions of said conduit.
15. In heating apparatus, in combination, a radiating system, an injector connected to said radiating system and having an inner portion movable with respect to its outer portion and shaped to vary the opening through one of its passages by such movement, means adapted to lead steam through one of the passages of said injector on its way to said radiating system, and thermostatic means connecting said injector to said radiating system and arranged to control the relative position of said inner and outer portions of said injector.
16. In heating apparatus, in combination, a radiating system, an injector connected to said radiating system and having its inner portion movable with respect to its outer portion and shaped to vary the opening through one of its passages by such movement, means adapted to lead steam through one of the passages of said injector, and a conduit leading from said radiating system and connected to one portion of said injector to move the same as the conduit expands and contracts.
17. In a heating system, the combination with a radiating system, of a source of heat supply, a feed conduit for the radiating system one end of which leads therein and which has a fixed relation thereto, a discharge conduit leading from said radiating system, one end of which has fixed relation thereto, the opposite ends of said conduits being relatively movable due to different co-efficients of expansion of the metals of which they are constituted, an injector connected with the source of supply and leading into said feed conduit, and a valve controlling the passage of steam through said injector operable by the differential expansion and contraction of said feed and discharge conduits.
18. In heating apparatus, in combination, an injector having an inner portion movable with respect to its outer portion and shaped to vary the opening through one of its passages by such movement, means adapted to lead steam through one of the passages of said injector, a conduit connected to the inner portion of said injector, and a second conduit connected to the outer portion thereof, said parts being proportioned to move said inner portion of said injector with respect to its outer portion in accordance with the difference in expansion and contraction between said conduits.
19. In heating apparatus, in combination, a continuous steam conduit open to the atmosphere and having an injector member positioned intermediate its length and adapted to lead air and steam from the portion upon one side of the injector member to the portion upon the other side thereof, an inlet valve associated with said injector member and arranged to be controlled in accordance with the difference in expansion and contraction of the different portions of said conduit.
20. In a car heating system, in combination with the train pipe, of a radiating circuit located within the car, a feed conduit connected with the train pipe and with said radiating circuit, a discharge conduit leading from said radiating circuit, and a valve operated by differential expansion and contraction of said feed and discharge conduits for controlling the amount of steam admitted into said radiating system.
21. In a car heating system, the combination with the train pipe, of a radiating circuit located within the car, a feed conduit connected with the train pipe and said radiating circuit, means for injecting steam into said feed conduit, a valve for controlling the amount of steam injected therein, and a discharge conduit, said feed and discharge conduits operating through differential expansion and contraction to move said injector and thereby open and close said valve.
22. In a car heating system, the combination with the train pipe, of a radiating system open to the atmosphere and located within the car, a feed conduit connected with the train pipe and with said radiating system and open to the atmosphere through its connection with said radiating system, means for injecting a mixture of steam and air into said conduit, a discharge conduit for said radiating system, and a valve the operation of which is determined by differential expansion and contraction of said feed and discharge conduits for controlling the amount of steam injected into the said feed conduit.
23. In a car heating system, in combination with the train pipe, a radiating system located within the car, a feed conduit connected with said radiating system, a dis-

charge conduit leading from said radiating system, a conduit open to the atmosphere connected with said discharge conduit, a tubular injector member extending within 5 said feed conduit and having a sliding connection therewith, a valve seat formed within said conduit, and a valve formed at the inner end of said injector member, the differential expansion and contraction of said 10 feed and discharge conduits operating to move said injector member to open and close said valve in accordance with the internal heat conditions of the radiating system.

24. The combination, in a car heating system, of a train pipe, a radiating system comprising a line of connected piping located within the car, a feed conduit connected with the train pipe and with said piping, a discharge conduit for said line of connected 20 piping, a conduit connected with said discharge conduit and having an opening communicating with the atmosphere, an injector member having fixed relation with said last-mentioned conduit and connecting the 25 same with said feed conduit, said injector member extending within said feed conduit and having a sliding connection therewith, a valve seat formed within said feed conduit, and a valve formed at the inner end of 30 said injector member, said feed and discharge conduits being formed of metals having different co-efficients of expansion and constituting a thermostatic device to open or close said valve in accordance with the 35 internal heat conditions of the system and thereby determine the amount of steam to be injected therein.

25. In a car heating system, in combination with the train pipe, a radiating system located within the car, a feed conduit connected with the train pipe and with the upper portion of said radiating system, a discharge conduit leading from the lower portion 40 of said radiating system and discharging into the atmosphere, a conduit connecting said discharge conduit and said feed conduit, said last-mentioned conduit constituting means for injecting steam into said feed conduit, and a valve operated through 45 differential expansion and contraction of said feed and discharge conduits adapted to control the operation of said injecting means.

26. In car heating apparatus, in combination, a radiating conduit adapted to lead 50 steam from a point intermediate the length of the car longitudinally thereof and return the same to a point adjacent the inlet, an injector positioned to connect the discharge end of said conduit to the supply end 55 through one of its passages, and means adapted to lead live steam into the other passage of said injector, said injector adapted to throttle the passage from the steam supply to the supply end of said conduit by 60 the difference in expansion and contraction

of the supply and discharge portions of said conduit.

27. In a vapor heating system for railway cars or like structures, the combination with the train pipe, of a radiating system located 70 within the car, a tubular member of relatively low co-efficient of expansion connecting the train pipe to the said radiating system, a tubular member of relatively high co-efficient of expansion for discharging the 75 water of condensation from said radiating system, both of said members being open to the atmosphere, an injector interposed between the train pipe and said first-mentioned tubular member, and a valve for controlling the amount of steam injected therein, the differential expansion and contraction of said tubular members operating to open and close said valve in accordance with the internal heat conditions of the radiating 80 system.

28. In combination with a car heating system, a system of piping arranged in the car and in free connection with the atmosphere, a train pipe adapted to supply a heating 85 medium to said radiating system, a feed conduit interposed between the train pipe and the radiating system, a discharge conduit leading therefrom, means for injecting a mixture of steam and air into said conduit, 90 and a valve for controlling the amount of said mixture injected therein, said feed and discharge conduits being formed of metals of different co-efficients of expansion and operating as a thermostatic device to regulate the operation of said valve.

29. In a car heating system, the combination with the train pipe, of a system of radiating pipes arranged within the car and adapted to heat the same, a train pipe 105 adapted to supply a heating medium to said radiating pipes, a valve interposed between the train pipe and said radiating pipes, a feed conduit interposed between said valve and said radiating pipes, a discharge conduit leading from said radiating pipes, said feed and discharge conduits being open to the atmosphere, and means for injecting a mixture of steam and air into said feed conduit, said feed and discharge conduits being 110 formed of metals having different co-efficients of expansion and operating as a thermostatic device to open and close said valve in accordance with the temperature of the 115 circulating heating medium.

30. In a heating system for railway cars or like structures, the combination with the train pipe, of a system of radiating pipes arranged within the car and adapted to heat the same, a feed conduit for connecting said 120 train pipe with the radiating pipes, a discharge conduit for said radiating pipes adapted to discharge freely into the atmosphere, a tubular injector member connecting said discharge conduit with the feed conduit, 125 130

the injector portion of said tubular member being arranged intermediate the ends of said feed conduit whereby steam from the train pipe will be injected therein, a valve seat 5 arranged within said feed conduit, a valve portion formed upon said injector, said feed and discharge conduits being formed respectively of metals of relatively low and relatively high co-efficients of expansion and 10 constituting a thermostatic device for automatically operating said valve in accordance with the internal heat conditions of the heater, and means for changing the relation of said valve portion with respect to its seat. 15 31. In a heating system, the combination with a radiating system, of a feed conduit leading thereto, a discharge conduit leading therefrom, and a valve for controlling the

admission of steam to said radiating system, said feed and discharge conduits constituting 20 thermostatic actuating mechanism for operating said valve.

32. In a heating system, the combination with a radiating system, of a feed conduit leading thereto, and a discharge conduit 25 leading therefrom, said feed and discharge conduits constituting a thermostat for controlling the admission of steam to said radiating system.

In testimony whereof I affix my signature, 30 in the presence of two witnesses.

ROBERT M. DIXON.
